UNITED STATES PATENT OFFICE.

LAWSON B. SHELTON, OF LOS ANGELES, CALIFORNIA.

CASEMENT WINDOW AND DOOR.

1,304,611.

Specification of Letters Patent. Patented May 27, 1919.

Application filed May 7, 1918. Serial No. 233,177.

To all whom it may concern:

Be it known that I, LAWSON B. SHELTON, a citizen of the United States, residing at Los Angeles, in the county of Los Angeles

5 and State of California, have invented a new and useful Improvement in Casement Windows and Doors, of which the following is a specification.

My object is to produce an inwardly opening casement window or door, of simplified construction which, when closed, is more weather proof, and which has a ventilator, and my invention consists of the novel features herein shown, described and claimed.

15 In the drawings;

Figure 1 is a bisected perspective inside face view of a window embodying the principles of my invention.

Fig. 2 is a top plan sectional view taken 20 upon the lines 2—2 of Fig. 1.

Fig. 3 is an enlarged fragmentary sectional view on the lines of arrows 3—3 of Fig. 2 and showing the principal operating features of my invention.

25 Referring to the drawing in detail;

The sash 1 is hinged to stile 2, and operates therewith. A housing, or supporting frame, consisting of members 3, 4, 5, 6 and 7, some of which are matched to fit and 30 nearly surround lift 2. A balancing weight 8 with cord 9, which passes over upon pulley 10, down between member 4 and stile 2, and may be suitably fastened thereto. A gravity catch 13, inserted into stile 2 and 35 adapted to swing, and having its upper end curved toward sash 1 to make contact therewith and be actuated thereby to enter into shoulder 14 of member 4. A ventilator 15 extends across window opening at the top, 40 hinged or pivoted to swing open, and the lower inner side to lap against the upper outer face of sash 1. When it is desired to open the window, the sash 1 is raised and swung open, freeing gravity catch 13 to 45 settle into shoulder 14.

When it is desired to close the window, the sash 1 is shut, disengaging the gravity catch 13, and then lowered to sill 18 on weather side of stool 19.

I desire to call especial attention to the 50 fact that my invention is adapted to windows having right and left sash that meet, or otherwise, and may operate independently, or have their stiles rigidly connected across and above sash and operate together 55 in raising. And that when used for doors, the construction is identical with that of casement windows, the stool effect of which may be made in a suitable way to produce the same weather proof result. It is obvious 60 that I have invented a new and useful casement window and door of simplified construction, easy to operate, and more weather proof about the base.

What I claim and desire to secure by Letters Patent of the United States is;

1. The combination with a window frame having the usual inside stool of a sash, mounted to swing inward and also capable of lifting; to be pressed over the stool and 70 be dropped to lap the stool when in a closed position, and a closure strip to cover the space exposed at the top of the sash when the latter is so lowered; said closure strip being hinged so that it may be swung up to 75 open the space for ventilation purposes.

2. The combination with a window frame of a sash mounted to swing inward on a stile arranged to lift in order that the sash may pass over the stool, and a catch pivoted upon 80 said stile, and engageable in a recess to hold the stile in an elevated position, the parts being so arranged that the swinging of the sash into the place of the frame detaches the catch and permits the sash to drop behind 85 the stool.

LAWSON B. SHELTON.
